US00D579870S

(12) **United States Design Patent**
Dunbar et al.

(10) **Patent No.:** **US D579,870 S**
(45) **Date of Patent:** **** Nov. 4, 2008**

(54) **PORTABLE BACKUP POWER DEVICE**

(75) Inventors: **Grant Iverson Dunbar**, North Vancouver (CA); **Robert Bruce Prior**, Burnaby (CA); **Peter Tai Kwong Cheung**, Richmond (CA)

(73) Assignee: **Xantrex International**, St. Michael (BB)

(**) Term: **14 Years**

(21) Appl. No.: **29/287,126**

(22) Filed: **Jun. 29, 2007**

(51) **LOC (8) Cl. 13-01**

(52) **U.S. Cl. D13/116; D13/110**

(58) **Field of Classification Search D13/110, D13/116, 123, 124, 137.2, 139.1, 139.8, 184, D13/199; 174/53, 58; 307/85, 150, 151; 363/15, 95, 103, 146**

(57) **CLAIM**

The ornamental design for a portable backup power device, as shown and described.

DESCRIPTION

FIG. 1 is a perspective view of a portable backup power device showing our new design;

FIG. 2 is a front elevational view thereof;

FIG. 3 is a right side view thereof;

FIG. 4 is a left side view thereof;

FIG. 5 is a top plan view thereof;

FIG. 6 is bottom plan view thereof; and,

FIG. 7 is a rear view thereof.

The broken lines showing are for illustrative purposes and form no part of the claimed design.
